(57) **CLAIM**

The ornamental design for a lock actuator grip for a torch tip of a torch handle, as shown and described.

DESCRIPTION

FIG. 1 is a front view of a lock actuator grip for a torch tip of a torch handle showing my new design;

FIG. 2 is a top plan view thereof;

FIG. 3 is a left side view thereof;

FIG. 4 is a right side view thereof;

FIG. 5 is a rear view thereof;

FIG. 6 is a front view of the lock actuator grip for a torch tip of a torch handle in a different environment;

FIG. 7 is a top plan view thereof;

FIG. 8 is a left side view thereof;

FIG. 9 is a right side view thereof; and,

FIG. 10 is a rear view thereof.

The broken line showings of portions of the torch handle are included for the purpose of illustrating environmental structure and form no part of the claimed design.
